PHOTOGRAPHIC FLASHLAMP HOLDER FOR CAMERAS

Lester A. Dine and Edgar S. Lemmey, Levittown, N. Y.

Application April 22, 1954, Serial No. 30,123

Term of patent 14 years

(Cl. D61—1)

Fig. 1.

Fig. 2.

Fig. 3.

Fig. 4.

To all whom it may concern:

Be it known that we, Lester A. Dine and Edgar S. Lemmey, both citizens of the United States, both residing at Levittown, county of Nassau, State of New York, have invented a new, original, and ornamental Design for a Photographic Flashlamp Holder for Cameras, of which the following is a specification, reference being had to the accompanying drawings, forming a part thereof, wherein:

Figure 1 is a front elevational view of a photographic flashlamp holder for cameras, showing our new design;

Figure 2 is a side elevational view thereof;

Figure 3 is a rear elevational view thereof; and

Figure 4 is a top plan view thereof.
The side of the photographic flashlamp holder for cameras not shown is the same as the side shown in Figure 2.

We claim:

The ornamental design for a photographic flashlamp holder for cameras, as shown and described.
